UNITED STATES PATENT OFFICE.

CHARLES ATHEY, OF PARIS, ILLINOIS.

HEATING STOVE.

Application filed November 16, 1921. Serial No. 515,608.

To all whom it may concern:

Be it known that I, CHARLES ATHEY, a citizen of the United States, residing at Paris, in the county of Edgar and State of Illinois, have invented a new and useful Heating Stove, of which the following is a specification.

This invention relates to a heating stove one of its objects being to provide a stove 10 which has means whereby heat can be radiated both outwardly and inwardly, the inwardly radiating heat serving to raise the temperature of a current of fresh air flowing through the stove from the bottom to 15 the top thereof while the outwardly radiating heat will raise the temperature of the air surrounding the stove.

Another object is to provide a stove of this character having practically twice the 20 efficiency of the usual type of drum heaters using gas or oil as a fuel, the construction of the stove being simple and durable.

With the foregoing and other objects in view which will appear as the description 25 proceeds, the invention resides in the combination and arrangement of parts and in the details of construction hereinafter described and claimed, it being understood that, within the scope of what is claimed, 30 changes in the precise embodiment of the invention shown can be made without departing from the spirit of the invention.

In the accompanying drawings the preferred form of the invention has been 35 shown.

In said drawings

Figure 1 is a view partly in front elevation and partly in section of the stove.

Figure 2 is a section on line 2—2, Figure 1.

Referring to the figures by characters of reference 1 designates the hollow base of the stove which can be supported on suitable legs 2 and is provided with a desired number 45 of air inlet openings 3. A burner indicated generally at 4 is mounted within this hollow base and access thereto may be had by opening a door 5 in the base. A fuel pipe 6 can be extended to the burner 50 and this burner can be of a type for use with either gas or liquid fuel.

Mounted on the base 1 is a drum 7 the bottom of which opens into the base while formed in the top of the wall of the drum 55 are outlet openings 8. A ring 9 extends outwardly from and rests on the drum and

is preferably downturned to form an apron 10 which serves to conceal the openings 8. Supported within the drum 7 is an inner radiator 11 preferably cylindrical and having its open upper end flared outwardly 60 at 12 and resting on the upper edge of the drum. This inner radiator is spaced from the drum and has its lower end rounded as shown at 13 and supported close to the 65 open lower end of the drum 7. This rounded end is directly above the burner 4 and constitutes a heat spreader. Air conducting flues 14 extend through the base 1 and are open at their ends, the upper 70 ends of these flues opening into the bottom portion of the inner radiator while the lower ends of the flues open through the bottom of the base 1.

A dome shaped cover 15 is mounted on 75 the ring 9 and has openings 16 therein through which heated air can flow freely.

The drum 7 may be suitably ornamented, as by means of an annular flange 17 and an imitation door 18.

The burner 4 is preferably of a type which will produce almost complete combustion of the fuel so that fumes of an objectionable nature will not be discharged into the surrounding atmosphere. When the 85 fuel is ignited at the burner the lower spreading portion of the inner radiator will be heated to a high temperature and the hot products of combustion together with the air that has passed into the 90 base through the openings 3 and has been heated, will flow upwardly through the space between the drum 7 and the inner radiator and thence outwardly through the 95 openings 8. Thus both the drum and inner radiator will be heated to a high temperature and the heat radiating outwardly from the drum 7 will raise the temperature of the surrounding atmosphere while the heat radiating inwardly from the radiator 11 will 100 raise the temperature of the air within the stove, thereby setting up a current through the flues 14 and the radiator 11 to the outlet openings 16. Obviously as a result of this arrangement the efficiency of the stove as 105 a heating medium will be greatly increased because of the increased size of the heat radiating area without an increase in the amount of fuel used.

The stove can be made very attractive 110 so as not to present an unsightly appearance when used in a room.

What is claimed is:—

A heating stove comprising a hollow base, a burner mounted therein, a drum mounted on and communicating at its lower end with the base, an inner radiator having an out-turned upper end bearing downwardly on the drum and supporting the radiator concentrically within and spaced from the drum, said radiator having a semispherical lower end, said end constituting a heat spreader, the lowermost portion of said end being supported above and close to the burner, and upwardly converging air conducting flues opening through the bottom of the base and through the bottom of the radiator at points remote from the center thereof, said burner

being located between the flues, and a cover mounted on the radiator and having apertures therein, there being vents within the wall of the drum adjacent the top thereof, 20 and an annular apron extending downwardly from the upper portion of the drum and constituting means for deflecting air escaping through the vents in the wall of the drum.

In testimony that I claim the foregoing as my own, I have hereto affixed my signature in the presence of two witnesses.

CHARLES ATHEY.
